US00D937851S

(12) **United States Design Patent** (10) Patent No.: **US D937,851 S**
Patel et al. (45) Date of Patent: **** Dec. 7, 2021**

(54) **DISPLAY SCREEN WITH GRAPHICAL USER INTERFACE**

(71) Applicant: **Google LLC**, Mountain View, CA (US)

(72) Inventors: **Kunal Patel**, San Francisco, CA (US); **Brendan Pascoe**, San Francisco, CA (US); **David Chiu**, Oakland, CA (US); **Rachel Been**, San Francisco, CA (US); **Sameer Bansal**, San Francisco, CA (US); **Ke Li**, New York, NY (US); **Damien Correll**, Brooklyn, NY (US); **Philippe Cao**, Brooklyn, NY (US)

(73) Assignee: **GOOGLE LLC**, Mountain View, CA (US)

(**) Term: **15 Years**

(21) Appl. No.: **29/737,893**

(22) Filed: **Jun. 12, 2020**

Related U.S. Application Data

(63) Continuation of application No. 29/645,448, filed on Apr. 26, 2018, now Pat. No. Des. 889,501.

(57) **CLAIM**

The ornamental design for a display screen with graphical user interface, as shown and described.

DESCRIPTION

The sole FIGURE is a front view of a display screen with graphical user interface, showing the new design.

The uneven-length broken line showing a display screen defines the boundary of the design and forms no part of the claim. The even-length dashed lines illustrate portions of the graphical user interface that form no part of the claimed design.
